UNITED STATES PATENT OFFICE.

ANTON S. SIMSACK, OF PHILADELPHIA, PENNSYLVANIA, ASSIGNOR OF ONE-THIRD TO
MORRIS APT, OF PHILADELPHIA, PENNSYLVANIA.

SPARK PLUG.

Application filed February 21, 1927. Serial No. 169,913.

The present invention is directed to an improved spark plug for use in connection with internal combustion engines.

The improvement is directed to a spark plug which comprises an ordinary base construction equipped with a customary core and main and secondary electrodes, together with an added unit such as is broadly designated as a current transformer, this transformer being 10 associated directly with and having electrical connection with the main electrode, so that the incoming electricity is transformed.

One of the prominent features of this invention is that it includes an unusually novel 15 transformer unit made expressly to cooperate with an ordinary spark plug base of a standard dimension.

It follows therefore, that my primary aim is to provide, as a new product of manufacture, a novel electrical current transformer 20 unit which can be connected with an ordinary spark plug base of the type having an insulator core carrying a short main electrode section.

An equally important aim is, however, to provide an exceptionally novel transformer which is particularly advantageous in that it changes the form of the current in such a manner that the resulting spark is somewhat 25 in the form of a brilliant and intense flash or distinguished from a short transient or jumping spark.

The invention is characterized by exceptional simplicity and convenience and arrangement of the parts, and is such as to insure rapid quantity output in the manufacture, easy assembly, and inexpensive production and sale, thus insuring a commercially 35 successful article having additional features and advantages, at a cost consistent with spark plugs now sold and marketed.

The particular details, their method of assembly, and cooperation in accomplishing the transformation will become readily apparent from the following description and drawings.

In the drawings:—

Figure 1 is a side elevation of an improved combination spark plug constructed in accordance with the present invention.

Fig. 2 is a central vertical section through the same with portions shown in elevation.

Fig. 3 is a horizontal section on the line 3—3 of Fig. 1.

Referring to the drawings in detail, it will

be seen that the reference character 1 designates a base. This comprises the customary metallic shell, having a wrench engaging portion 2 on its exterior and a reduced screw threaded neck 3 at its bottom adapted to tap 60 into the spark plug hole in the cylinder head. On the interior of this shell, is a downwardly tapered insulation core 4 carrying the main electrode 5 which extends down in spaced relation to the bottom of the neck 3 for cooperation with the customary right angular electrode or secondary contact 6. Appropriate packing 7 is interposed between the shoulders on the shell and core as shown in Fig. 2.

In the embodiment of the invention represented, the upper end of the electrode is enlarged and externally screw threaded as at 8 and a portion thereof projects above the insulation core.

The transformer unit is generally designated by the reference character 9. As shown better in Fig. 2, this transformer unit comprises a tubular casing 10 of appropriate insulation material open at its opposite ends. 80 A brass plug 11 is fitted into the lower end and hermetically sealed in place in any appropriate manner. This plug 11 is provided with a central socket which receives the upper extended screw threaded end of the electrode 8, thus coupling the unit through the medium of this electrode.

In this connection it will be noticed, however, that the lower end portion of the casing is provided with a shoulder and a steel 90 gland 12 is employed for cooperation therewith and for holding the unit firmly in place. The gland is of ordinary construction. Moreover, the lower end of this casing is formed with an annular groove into which 95 a packing ring 13 is fitted and this packing ring rests on top of the core 4 providing a tight connection.

Fitted into the upper end of the casing 10 is another brass plug, here designated by the reference character 14, and this carries a screw threaded stud 15 with a binding nut 16 thereon. This plug, as well as the other plug is formed on its interior with a socket for reception of an adjacent end of the insulator 105 rod 17.

A series of metallic rings 18 are fitted upon this rod and held in spaced relation by insulation washers 19, the washers being smaller in diameter than the rings. The 110

rings, in turn, are smaller in diameter than the interior of the casing, thus forming a sparking space 20 around the peripheral portions of these rings and washers.

5 The ignition which takes place here of course eliminates the oxygen in this chamber, and makes a vacuum chamber of it. In addition, there is a coiled spring 21 employed and this surrounds the rod 17 at the upper end, 10 bears against the uppermost ring, and against the under side of the plug.

Of course, in this invention, the usual wire terminal is connected with the plug in an ordinary manner, and the plug is tapped in 15 the cylinder head in the customary way. However, the arrangement of the multiplicity of disks provides for a new action in the formation of a multitude of spark gaps about the peripheral portions of the metallic disks 20 which are arranged in the spaced relation shown, and transform the current from a direct current to a high frequency current. The latter form of current, it is believed, is superior to that now produced, and comparative 25 tests show that a lengthy flash is produced at the sparking points instead of a short jumping spark.

It is believed unnecessary to make a further structural analysis or to attempt to describe the theory of operation, for it is believed that persons familiar with inventions 30 of this character, will understand the invention thoroughly after reading the description in connection with the drawings. As a 35 result of this, a more lengthy description is thought unnecessary.

Minor changes in shape, size, and relation, coming within the scope of the adjoined claims, may be resorted to if desired.

40 Having thus described my invention, what I claim as new is:—

1. A spark plug comprising an annular metallic shell provided with an externally screw threaded neck adapted to be tapped into 45 a cylinder head, a core of insulation material disposed within the shell and having its upper end terminating in inwardly spaced relation to the corresponding end of said shell, a main electrode embedded in said core, and having 50 its lower end extending down below the bot-

tom of the shell, a secondary electrode carried by the shell and co-operating with the first-named electrode, and a current transforming device comprising a hollow casing having upper and lower plugs of electricity 55 conducting material fitted in its opposite ends, the lower plug and lower end portion of said casing telescoping into said shell and being disposed in abutting relation with the core and having electrical connection with said electrode, and current transforming means within the casing embodying a multiplicity of metallic discs and intervening insulating and spacing washers, having their 60 peripheral portions spaced from the inner wall of the casing to provide a surrounding 65 sparking space.

2. A spark plug comprising a shell provided with an externally screw threaded neck adapted to tap into the screw threaded hole 70 in a cylinder head, a core of insulation material disposed within said shell, an electrode carried by said core, a secondary electrode carried by the shell and cooperable with the first-named electrode, and a current transforming device supported within said shell, 75 said device comprising an elongated tubular casing of insulation material, plugs fitted into the opposite open ends of the casing, said plugs being of electrical conducting material, 80 an axially aligned rod of insulation material located on the interior of the casing and having its opposite ends connected with said plugs, a set of metallic rings fitted upon said rod, a ring on one end of the set being in electrical connection with one of the plugs, a coiled spring surrounding the opposite end of said rod and engaging the adjacent ring, and the adjacent plug, and insulation washers 85 surrounding the rod and interposed between the rings and spacing the rings and washers being of a diameter less than the cross sectional diameter of the interior of the casing, to provide an annular sparking space around the peripheral portions of the rings and the 90 washers, and means on the upper plug for connection to a current supply wire.

In testimony whereof I affix my signature.

ANTON S. SIMSACK.
